PRESSURIZED DISPENSER

Santy M. Croce, Ronkonkoma, N. Y., assignor, by
mesne assignments, to Coty, Inc., New York,
N. Y., a corporation of Delaware

Application November 30, 1951, Serial No. 259,218

7 Claims. (Cl. 299—86)

1

This invention relates in general to dispensing apparatus and more particularly to improvements in devices for dispensing material from a container in response to gas therein under pressure.

It is an object of this invention to provide a perfume atomizer in which the perfume will be ejected from the container in response to gas pressure.

It is another object of this invention to provide an atomizer in which the liquid to be dispensed and the dispensing gas are contained in separate reservoirs.

It is a further object of this invention to provide an atomizer in which a metered amount of perfume will be ejected in response to the single actuation of its dispensing button.

Other objects and advantages of the invention will be apparent as it is better understood from the following description; which, when taken in connection with the accompanying drawing discloses a preferred embodiment thereof;

In the drawings

Figure 1 is a sectional view of the bottle embodying my invention;

Figure 2 is a sectional view of a modified form of my invention.

In Figure 1, a bottle, which is illustrated as being of glass, contains the fluid 2, in this case perfume, to be dispensed. The neck 3 of the bottle has a threaded portion 4 engaged with a cap 5. The cap 5 of the bottle is recessed at 6 to support a washer 7 for a purpose hereinafter described. A discharge nozzle 8 extends laterally from a central opening 9 in the cap 5 and is in communication with depending tube 10 extending toward the bottom of the bottle 1.

A gas reservoir supporting member 11 is seated on the top of the neck 3 of the bottle 1 supported on a circular flanged portion 12. The cap 5 is tightly screwed in place to rigidly hold the reservoir supporting member 11 in position. This gas reservoir supporting member 11 extends downwardly and is provided with a threaded portion 13 at its lower end. The gas containing reservoir 14 is threadingly engaged on portion 13 and contains the dispensing gas 15 therein.

A passage 16 in the reservoir supporting member 11 establishes communication between the chamber formed by 11 and the dispensing gas reservoir 14, and provides a valve seat for dispensing valve 17, seated within the chamber formed by gas reservoir supporting member 11 and biased upwardly in a manner hereinafter described against the cap 5. Valve 17 is reduced

2

at either end to form valve portions and at one end is extended to form a stem 18, terminating in a dispensing button 19 on the opposite side of the washer 7. Valve 17 is also formed with a spring seating ring 20 along its body. Valve spring 21 surrounds valve 17 and is seated at one end against ring 20 and at its other end on the lower portion 22 of the chamber 11. The valve spring 21 biases valve 17 upwardly so that escape from the chamber 11 is normally prevented.

The operation of this form of my invention is as follows:

The dispensing gas 15, such as "aerosol," contained in chamber reservoir 14 is partially vaporized to fill the volume or chamber formed by reservoir supporting member 11. Escape of this gas from this chamber, however, is prevented since valve 17 is biased upwardly by action of spring 21 to close passage 9. When the operator desires to dispense some of the contained fluid 2, he depresses button 19 to move valve 17 downwardly opening the passage 9 and at the same time closing the passage 16. This allows the gas in the chamber formed by reservoir supporting member 11 to escape through passage 9 past nozzle 8. In doing so, the gas sucks up some of the fluid 2 from the container 1, atomizes it and discharges it into the atmosphere through nozzle 8. It will be recognized that the flow of gas under pressure through discharge nozzle or dispensing passage 8 lowers the atmospheric pressure above the open upper end of tube 10 and creates a suction therein.

It is obvious that since only a certain amount of gas is released by a single depression of the button 19, only a certain amount of perfume will be discharged thereby. When the operator removes his finger from button 19, the valve 17 is urged upwardly under action of springs 21 to close passage 9 and open passage 16, thus allowing additional dispensing gas 15 to fill the chamber 11. The apparatus is now ready for a second cycle of operation.

In the form of my invention shown in Figure 2, I have modified my dispensing apparatus so that the amount of perfume dispensed is solely under the control of the operator allowing her to dispense any desired amount in response to a single actuation of the dispensing button. In this figure, the subscript "a" will be added to those parts which are similar to those found in Figure 1.

A bottle 1a containing perfume 2a is formed with a neck 3a having a threaded portion 4a is threadingly engaged with a cap 5a. The cap 5a

is recessed at 6a and provided with a washer 7a. A nozzle 8a is formed in the cap 5a in communication with chamber 9a and in communication with tube 10a extending downwardly into the perfume reservoir. Gas reservoir supporting member 11a is formed with a flange portion 12a which rests upon and is held between the neck of the bottle 3a and the cap 5a. Chamber 11a extends downwardly and is formed with a threaded portion 13a at its lower end to which is attached gas reservoir 14a containing the dispensing gas 15a. The chamber 11a is in communication with the gas reservoir 14a by virtue of the passage 16a. A valve 17a is seated against the cap 5a under spring action. The valve 17a is formed with an extension 18a terminating in a button 19a. Valve biasing spring 21a bears against the cap 19a and the washer 7a to force the valve 17a upwardly normally closing passage 9a.

When the operator wishes to dispense perfume from this modification, he merely pushes the button 19a downwardly allowing the gas 15a to escape chamber 9a through nozzle 8a causing perfume to be drawn upward through tube 10a and dispensed in the usual manner.

I have described what I believe to be the best embodiments of my invention. I do not wish, however, to be confined to the embodiments shown, but what I desire to cover by Letters Patent is set forth in the appended claims.

I claim:

1. An article of manufacture comprising a cap for an atomizer having a dispensing passage, a tube extending from said dispensing passage and being open at both ends thereof, one open end communicating with the outside atmosphere and the other open end being adapted to be immersed in a liquid to be dispensed, a reservoir suspended from said cap and adapted to contain gas under pressure, said reservoir having an exit passage, said exit passage being in communication with said dispensing passage, and a valve in the path of, and in operative relationship with said exit passage, said dispensing passage being adjacent to and communicating with said one open end of said tube and also communicating with the outside atmosphere whereby a flow of gas under pressure from said reservoir exit passage through said dispensing passage lowers the pressure at said one open end of the tube and creates a suction therethrough.

2. An article of manufacture comprising a cap for an atomizer having a dispensing passage, a vertically depending tube extending from said dispensing passage and being open at both the upper and lower ends thereof, the open upper end being open to the outside atmosphere and the open lower end being adapted to be immersed in a liquid to be dispensed, a reservoir suspended from said cap and adapted to contain gas under pressure, a chamber in said reservoir having an entrance and exit passage, said exit passage being in communication with said dispensing passage, said entrance passage being in communication with said reservoir, and a valve in the path of, and in operative relationship with both said passages and normally closing said exit passage, said dispensing passage being adjacent and open to said open upper end of said tube and being likewise open to the outside atmosphere whereby a flow of gas under pressure from said exit passage through said dispensing passage lowers the atmospheric pressure above said depending tube and creates a suction therethrough.

3. A liquid dispensing unit comprising a frangible container for the liquid to be dispensed, said container having a neck portion, an atomizer cap for said container secured on said neck portion, said cap having a dispensing passage, a vertically depending tube extending from said dispensing passage into said container and being open at both the upper and lower ends thereof, the open upper end being open to the outside atmosphere, a dispensing gas reservoir for housing gas under pressure, said gas reservoir including an upper chamber supported from said cap and said gas reservoir extending into said container so that it is normally substantially surrounded by the liquid to be dispensed when the container is filled with liquid, said chamber having an exit passage, said exit passage being in communication with said dispensing passage, and a valve in said chamber and in operative relationship with said exit passage, said dispensing passage being adjacent and open to said open upper end of said tube and being likewise open to the outside atmosphere whereby a flow of gas under pressure from said exit passage through said dispensing passage lowers the atmospheric pressure above said depending tube and creates a suction therethrough.

4. A liquid dispensing unit comprising a frangible container for the liquid to be dispensed, said container having a neck portion, an atomizer cap supported on said neck portion, said cap having a dispensing passage, a vertically depending tube extending from said dispensing passage into said container and being open at both the upper and lower ends thereof, the open upper end being open to the outside atmosphere, a dispensing gas reservoir supported between said neck portion and said cap, and extending into said container so as to be normally surrounded by the liquid to be dispensed, a chamber above said reservoir and having an entrance and an exit passage, said exit passage being in communication with said dispensing passage, said entrance passage being in communication with said reservoir, and a valve in said chamber and in operative relationship with both said passages and normally closing said exit passage, said dispensing passage being adjacent and open to said open upper end of said tube and being likewise open to the outside atmosphere whereby a flow of gas under pressure from said exit passage through said dispensing passage lowers the atmospheric pressure above said depending tube and creates a suction therethrough.

5. A liquid dispensing unit comprising a frangible container for the liquid to be dispensed, a closure for said container, a dispensing nozzle passage formed in said closure, a depending tube extending from said dispensing passage into said container and being open at both the upper and lower ends thereof, the open upper end being open to the outside atmosphere, a dispensing gas reservoir charged with the gas under pressure extending from said closure into the interior of the container so as to be normally, substantially surrounded by the liquid when the container is filled with liquid, said reservoir having an exit passage in communication with said dispensing nozzle passage and valve means between said reservoir and said dispensing nozzle passage and normally closing said exit passage, said dispensing nozzle passage being adjacent and open to said open upper end of said tube and being likewise open to the outside atmosphere whereby a flow of gas under pressure from said exit passage

sage through said dispensing passage lowers the atmospheric pressure above said depending tube and creates a suction therethrough.

6. A liquid dispensing unit according to claim 5 and wherein said dispensing nozzle passage extends horizontally in said closure and said depending tube extends vertically therefrom.

7. A dispensing unit comprising a frangible container for the liquid to be dispensed, a reservoir containing a supply of gas under pressure, 10 said reservoir being disposed within and substantially centrally of said container so as to be normally surrounded by the liquid to be dispensed when the container is filled with the liquid, dispensing nozzle passage means supported by said container, a depending tube extending from said dispensing nozzle passage means and into the interior of the container, said tube being open at both the upper and lower ends thereof, the open upper end being open to 20 the outside atmosphere, said dispensing nozzle

passage means including a passageway adjacent and open to the said open upper end of said tube and being likewise open to the outside atmosphere, and valve means between said reservoir and said passageway whereby gas from said reservoir may be permitted to flow through said passageway so as to lower the atmospheric pressure above said depending tube and create a suction therethrough.
